UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

MACHINE FOR INSERTING FASTENINGS.

Application filed February 24, 1919. Serial No. 278,695.

To all whom it may concern:

Be it known that I, GEORGE GODDU, a citizen of the United States, residing at Winchester, in the county of Middlesex and 5 State of Massachusetts, have invented certain Improvements in Machines for Inserting Fastenings, of which the following description, in connection with the accompanying drawings, is a specification, like 10 reference characters on the drawings indicating like parts in the several figures.

This invention relates to machines for inserting fastenings, and, by way of illustration, is herein shown as embodied in a machine for inserting screw-threaded fastenings in the soles of boots and shoes of the type disclosed in United States Letters Patent No. 490,621, granted Jan. 24, 1893, on an application of Louis Goddu.

20 In the operation of machines of the type disclosed in said Letters Patent, it is necessary that the insertion of fastenings be suspended while a finished piece of work is being removed from the machine and a fresh 25 piece substituted therefor and frequently during operation on a single piece of work. The screw-threaded wire from which the fastenings are formed is thrust into the work by a wire-carrying spindle which communicates 30 its motion to the other operating parts of the machine. The spindle is operated at high speed, and both the spindle and the operating parts driven by it are heavy. Consequently, their momentum is such that 35 quick and frequent stopping of the machine would cause excessive wear and breakage of its elements, thus making it impracticable to discontinue the operation of the entire machine whenever it is necessary to suspend 40 the insertion of fastenings. The machine is, therefore, operated continuously, the insertion of fastenings being suspended when desired by maintaining the wire feeding mechanism out of engagement with its actuator 45 by manually controlled means. Inasmuch as there is no certainty as to the time in the cycle of operations of the machine when the manually controlled means will be actuated, the manner of engagement of the wire feed-

50 ing means with its continuously moving actuator upon the resumption of the insertion of fastenings may be such as to cause a fastening shorter than the proper length for a given thickness of work to be inserted or the

machine may fail entirely to insert a fasten- 55 ing in the first fastening location. Various attempts have heretofore been made to provide satisfactory mechanism for suspending the insertion of the fastenings but so far as known, none of these mechanisms have gone 60 into general use, due, largely, to the added expense involved in embodying them in the machine.

One of the objects of this invention is to provide mechanism which will insure that 65 the first fastening inserted upon the initiation of the insertion of fastenings will be of full length, which will be efficient and reliable in operation, and which will, at the same time, be simple in construction and 70 readily applicable to such machines as at present constructed and consequently capable of being embodied in the machines at a low cost. Preferably, the mechanism is so constructed and arranged as to cause the 75 feeding means to engage its actuator substantially at the beginning of a cycle of operations of the machine which ends with the severance of the section of the wire inserted in the work from the wire. 80

An important feature of the invention resides in the provision of manually operated means for suspending the insertion of fastenings and means for automatically controlling the operation of the manually operated 85 means so as to cause the insertion of fastenings to be resumed at the appropriate time in the cycle of operations of the machine. Preferably, the manually operated means comprises a member operable when in one 90 position to render the wire feeding means inoperative and movable from such position to cause the machine again to feed the wire, the member being normally precluded from such movement by a stop interposed in its 95 path of movement and operatively connected with the wire severing means.

In machines of said type the work support is raised to work clamping position by a treadle, and heretofore the construction of 100 the machine has been such that the work support dropped immediately upon the release of the treadle. Inasmuch as the treadle might be released by the operator at any time in the cycle of operations of the 105 machine, the work support was liable to be lowered before the last fastening desired was completely inserted.

Another object of the invention is to insure that the work support will not be lowered until the last fastening has been completely driven, and to this end, one of the features of the invention aims to provide means controlled by the wire severing means for retaining the work support in work clamping position regardless of the time in the cycle of operations of the machine when the treadle is released by the operator until the last fastening desired has been fully inserted into the work and severed from the wire.

Other objects and features of the invention will appear as the description proceeds and will be pointed out in the appended claims.

Fig. 1 of the drawings is a view in side elevation of a machine embodying the invention.

Fig. 2 is a view on an enlarged scale taken from the other side of the machine and showing the means for raising and lowering the work support.

Fig. 3 is a plan view partly in section of the parts shown in Fig. 2.

Fig. 4 is a plan view of the means for suspending the feed of the wire and the operating and controlling means therefor taken along the line 4—4 of Fig. 1, and

Fig. 5 shows the same parts as Fig. 4 in elevation.

The machine frame comprises a column 2 having mounted thereon a head 4 which carries the fastening inserting instrumentalities of the machine including a wire-carrying spindle 6. The wire used in the machine is threaded and is screwed into the work by rotation of the spindle, the wire being fed downwardly by devices including a wire feed lever 8 operated by a cam 10 on one of a pair of lateral shafts 12 journaled on the head 4 of the machine and driven from the wire spindle 6.

The work to be operated upon is supported on a work support 13 in the form of a horn carried by a horn post 14 to which is secured a bracket 15 in which is mounted a rod (not shown) co-operating with a measuring rod 16 depending from the rear end of the wire feed lever 8 to regulate the extent of movement of the wire feeding devices of the spindle 6 to cause the insertion into the work of a section of the wire equal in length to the thickness of the work. The section of the wire inserted into the work is severed from the remainder of the wire to form an individual fastening by mechanism indicated generally at 17 and operated by devices driven from the cam shaft and comprising a link 18 (see Fig. 1).

The operating mechanism for the machine comprises a driving shaft 19 the movement of which is transmitted to the wire-carrying spindle 6 by pulleys 20, 21 and 22, and

which is governed in its operation by clutch mechanism 23 controlled by a treadle 24. The elements of the machine hereinbefore described constitute in themselves no part of the present invention for which reason a more detailed description of them is deemed unnecessary.

As hereinbefore pointed out, the wire carrying spindle 6 and the parts operated thereby are relatively heavy, and the wire-carrying spindle is rotated at high speed so that a quick stoppage of the rotation of the spindle would entail so great a jar on the machine as to be likely to cause breakage of its parts. To the end that the insertion of fastenings by the machine may be suspended without discontinuing the operation of the entire machine, the measuring rod 16 is provided with a collar 25, Figs. 4 and 5, and a finger 26 pivoted at 28 on the head 4 of the machine is designed to be interposed beneath the collar 25 to hold the wire feed lever 8 away from the face of the cam 10. The movement of the finger 26 toward the rod 16 is limited by an adjustable stop 29 (Fig. 4). For moving the finger from beneath the collar 25 so as to cause the feeding of the wire to be resumed, I provide a rod 32 having a collar 34 formed with a lug 36 disposed for engagement with one side of the free end of the finger. The rod 32 also has mounted thereon a collar 38 provided with a lug 40 arranged for engagement with the other side of the finger 26 to move it beneath the collar 25 when it is desired that the feeding of the wire be again suspended.

The rod 32 is preferably adapted for control by the operator and may be moved at any time in the cycle of operations of the machine, whereas the invention aims to cause the wire feeding means to become operative only at a predetermined time in the cycle of operations of the machine, such that the first fastening inserted will be of full length. Accordingly, the collar 34 is loosely mounted on the rod 32 and is yieldingly urged in the direction of the finger 26 and against the collar 38 by a spring 42 coiled about the rod 32 and connected at one end to the collar 34 and at its other end to a collar 43 fixed to the rod 32. Upon movement of the rod 32 in an appropriate direction, the spring 42 presses the lug 36 against the finger 26. If, however, the finger 26 is prevented from movement at the time when the rod 32 is operated, the spring 42 will permit movement of the collar 34 on the rod, being itself put under tension so as thereafter to exert a force tending to move the finger from wire feed suspending position. Preferably, and in the illustrated construction, the rod 32 is moved to carry the finger 26 from beneath the collar 25 by an arm 44 extending inwardly from the rod and designed to be engaged by a cam surface 46 formed on a

treadle lever 48 having its hub mounted loosely on a shaft 50 fixed in a bracket 51 depending from the frame of the machine and in the other direction by a spring 53 coiled 5 about the rod 32 and connected at one of its ends to the rod and at its other end to the head 4 of the machine.

Normally interposed in the path of movement of the finger 26 so as to preclude its 10 movement from wire feed suspending position under the impulse of the spring 42 is a stop 54 carried by a stud slidably mounted in a bearing 56 of an arm 58 constituting part of the wire severing mechanism operated by the link 18. The stop 54, as shown, 15 is T-shaped having one of its arms projecting in the direction of the finger 26 and being disposed to overlie the finger upon movement of the finger from beneath the collar 20 25. A spring 60 is interposed between the arm 58 and a collar 62 on the stud of the stop 54 to permit downward movement of the arm 58 when the finger 26 is disposed beneath the projection of the stop without 25 breakage of the parts. As will be understood from the foregoing, the stop 54 operates automatically to control the movement 30 of the finger from wire feed suspending position, the projection on the stop being lifted 35 from the path of the finger 26 by the wire severing mechanism substantially simultaneously with the operation of the wire severing mechanism so that the wire feeding means is made operative at the beginning of 40 a cycle of operations of the machine ending with the severance of the wire. Stop 54 is retained in elevated position by the presence of finger 26 beneath it as long as the machine continues to operate to insert fastenings.

In accordance with the invention, means is provided for raising the work support to work clamping position simultaneously with the initiation of the insertion of fastenings. 45 In the illustrated construction, such mechanism comprises a lever 64 fulcrumed at 66 to the horn post 14 and operated by a rod 68 pivoted at 70 to the operating lever 64 and normally pressed downwardly by a 50 spring 72 which consequently tends to maintain the work support in elevated position. The rod 68 is operated from the cam shaft of the machine by means comprising the usual pawl and ratchet mechanism (not 55 shown) for compensating the movements of the work support to the thickness of the work carried thereby. The operating lever 64 is supported by a lever 74 loosely mounted on the shaft 50 and fulcrumed to the operating lever at 76 in such manner as to form 60 a toggle with the portion 78 of the lever. The supporting lever 74 in turn is formed with an arm 80 inclined upwardly from the shaft 50, and mechanism is provided for operating the supporting lever of a form such

as to take the weight of the work support and its associated parts from the operator, such mechanism comprising a pin 82 carried by a wiper arm 85 sleeved on a shaft 86 also fixed in the frame of the machine and 70 co-operating with a block 83 secured to the arm 80 of the supporting lever 74 by screws 84. When the work support is in work clamping position, the arm 85 is disposed substantially at right angles to the arm 80 75 of the supporting lever so that a force exerted downwardly at 76 as by pressure upon the work will be transmitted through the arm 85 to its shaft 86 with no tendency to turn the shaft. The sleeve 87 which carries 80 the arm 85 is operated by a sector gear 88 carried by an arm 89 extending upwardly from a yoke-shaped portion of the lever 48 underlying the shaft 50. The gear 88 meshes with teeth of a toothed flange 90 on the sleeve 87, the construction being such that the depression of the treadle 48 causes movement of the sector gear to carry the arm 85 to a position to elevate the horn. The shafts 50 and 86 are braced by an arm 91 bolted 90 on the shafts and formed at its upper end with a bracket 92 having an inwardly extending portion overlying the flange 90 of the sleeve 87.

The initial movement of the supporting 95 lever 74 upon depression of the treadle causes the lever 64 to swing about the point 70, thus elevating the horn 13 and the work supported thereon. After the work has been carried against the foot plate of the machine, however, the continued movement of the lever 74 moves the lever 64 about the point 66 compressing the spring 72. The normal compression of the spring 72 may preferably be adjusted, such adjustment, in 100 the illustrated construction, being provided for by a set screw 93 threaded into an ear 94 on the bracket 92. The further screw 93 is set in, the less fulcrum 76 can be raised, and accordingly the less will lever 78 be 105 rocked about fulcrum 66 with a correspondingly less compression of spring 72. The sector gear 88 is adjustably connected to its arm 89 by pin and slot connections 95 and a set screw 96 threaded into the arm and bearing against the rear face of the gear. 110

Inasmuch as the horn 13 is under the control of the treadle 48, the release of the treadle by the operator, in the absence of mechanism other than that hereinbefore described, would cause the work support to be lowered immediately thereafter. The operator may, however, release the treadle at any time in the cycle of operations of the machine, in consequence of which the work 120 support might be lowered at a time when the final fastening was only partially inserted into the work, so that such fastening would project from the work. In order to insure that the final fastening will be fully inserted 125 130

and to enable the efficient operation of the wire severing mechanism in severing the section of the wire inserted in the work from the wire, I provide mechanism for maintaining the work support in work clamping position until the final fastening has been fully inserted and severed from the wire. Preferably, and as shown, such mechanism comprises a latch 98 fulcrumed on a bracket 99 secured to the shafts 50 and 86, respectively, and disposed for engagement with a shoulder 100 on the treadle 48. The latch 98 is released from engagement with the shoulder 100 by operation of a rod 102 connected to the latch 98 and to an arm 104 integrally connected with the arm 58 which operates the wire severing mechanism.

The manner of operation of applicant's improved mechanism will, it is believed, be readily apparent from the foregoing description but may be briefly summarized as follows: When the treadle 48 is depressed by the operator, the horn 13 is immediately elevated from work receiving to work clamping position by the sector gear 88, sleeve 87, arm 85, supporting lever 74 and operating lever 64. The depression of the treadle also turns the rod 32 so that the spring 42 operates through the collar 34 whenever the stop 54 is carried out of the path of movement of the finger 26 to move the finger away from beneath the collar 25 on the rod 16 to permit the feeding of the wire to be resumed. The treadle is normally maintained in depressed position by the latch 98 which, regardless of the time in the cycle of operations of the machine when the operator removes his foot from the treadle, will permit the work support to be lowered from work clamping position only after the final fastening has been fully inserted and severed from the wire. The release of the treadle by the latch 98 permits the cam surface 46 to move downwardly away from the arm 44 and allows the rod 32 and the collar 38 carried thereby to be moved by the spring 53 so as to shift the finger 26 beneath the collar 25 again to suspend the feed of the wire.

Having described my invention, what I claim as new and desire to secure by Letters Patent of the United States is:—

1. In a machine of the class described, fastening inserting mechanism, means for suspending the insertion of fastenings during the continued operation of the machine, and positively operating means manually operable and automatically controlled to render the suspending means inoperative.

2. In a machine of the class described, fastening inserting mechanism, means for severing fastenings from fastening stock, means for suspending the insertion of fastenings during the continued operation of the machine, and manually operable means con-

trolled by the stock severing means for rendering the suspending means inoperative.

3. In a machine of the class described, means for inserting fastenings formed from wire, means for severing the fastenings from the wire, means for suspending the insertion of fastenings during the continued operation of the machine, manually operated means for rendering the suspending means inoperative, and means operatively connected with the wire severing means for controlling the movement of the suspending means by the manually operated means.

4. In a machine for inserting fastenings, wire feeding means, means for suspending the operation of the wire feeding means, manually operable means for rendering the suspending means inoperative, and positively operating automatic means for controlling the movement of the suspending means by the manually operated means.

5. In a machine for inserting fastenings, wire feeding means, means for suspending the operation of the wire feeding means, manually operable means for yieldingly urging the suspending means toward inoperative position, and means for positively controlling the movement of the suspending means to inoperative position.

6. In a machine for inserting fastenings, wire feeding means, manually operable means for suspending the operation of the wire feeding means, means tending to render the suspending means inoperative, and means operated in timed relation with the wire feeding means for positively maintaining the suspending means in operative position except at a predetermined time in the cycle of operations of the machine.

7. In a machine for inserting fastenings, wire feeding means, means for suspending the operation of the wire feeding means, manually operated means for yieldingly urging the suspending means toward inoperative position, and means operating positively and automatically to control the movement of the suspending means to inoperative position.

8. In a machine for inserting fastenings, wire feeding means, means for suspending the operation of the wire feeding means, and means for moving the suspending means to inoperative position comprising a rod, a lug yieldingly carried by the rod and tending to move the suspending means to inoperative position upon movement in one direction of the rod, and operator-controlled means for moving the rod.

9. In a machine for inserting fastenings, wire feeding means, means for suspending the operation of the wire feeding means, means for moving the suspending means to inoperative position comprising a rod, yielding connections between the rod and the suspending means, and operating means for

the rod comprising a treadle and co-operating parts between the treadle and rod for effecting angular movement of the rod.

10. In a machine for inserting fastenings, 5 wire feeding means, means for suspending the operation of the wire feeding means, a member for controlling the suspending means, means operative when the controlling member is in one position yieldingly to urge the suspending means to inoperative position, means for rendering the suspending means operative upon movement of the controlling member to another position, and means tending to move said controlling 10 member to said last-mentioned position.

11. In a machine for inserting fastenings, wire feeding means, means for suspending the operation of the wire feeding means, manually operated means for moving the 20 suspending means into and out of operative relation to the wire feeding means comprising a rod, a member yieldingly mounted on said rod and tending upon movement of the rod to one position to move the suspending 25 means to inoperative position, a second member carried by said rod and spaced from the first-mentioned member and operative upon movement of the rod to another position to render the suspending means operative, a 30 treadle for moving the rod to said first-mentioned position, and yielding means for moving the rod from said first-mentioned position to said second-mentioned position.

12. In a fastening inserting machine, wire 35 feeding means, means for suspending the operation of the wire feeding means, wire severing means, and manually operable means controlled by the wire severing means for rendering the suspending means inoperative.

13. In a fastening inserting machine, wire feeding means, means for suspending the operation of the wire feeding means, means for yieldingly urging the suspending means 45 toward inoperative position, wire severing means, and means operatively connected with the wire severing means for controlling the movement of the suspending means to inoperative position.

14. In a fastening inserting machine, wire feeding means, means for suspending the operation of the wire feeding means, means tending to render the suspending means inoperative, a stop normally interposed in the 50 path of movement of the suspending means, and means operated in timed relation with the wire feeding means for moving said stop out of the path of movement of the suspending means to permit the wire feeding 55 means to become operative at a predetermined time in the cycle of operations of the machine.

15. In a fastening inserting machine, wire feeding means, means for suspending the 60 operation of the wire feeding means, a stop

device normally interposed in the path of movement of the suspending means, wire severing means, and means operated by the wire severing means for moving the stop device out of the path of movement of the suspending means to permit the wire feeding means to be rendered operative substantially simultaneously with the operation of the wire severing means.

16. In a fastening inserting machine, wire 75 feeding means, a member for suspending the operation of the wire feeding means, means tending to move said member to inoperative position to render the wire feeding means operative, a stop device having a laterally projecting portion normally interposed in the path of movement of said member, and means for moving the stop device to carry the projecting portion of the device out of the path of movement of said member to 80 permit movement of said member to inoperative position.

17. In a fastening inserting machine, wire feeding means, a member for suspending the operation of the wire feeding means, means 90 tending to move the member out of operative position, a stop device having a laterally extending portion normally interposed in the path of movement of said member, and means for moving said stop device at a predetermined time in the cycle of operations of the machine to carry said projection out of the path of movement of said member to permit the member to move to inoperative position to render the wire feeding means operative, said moving means comprising a yielding connection operable to permit movement of the stop device relatively thereto upon engagement of the projecting portion of the stop device with said 95 member.

18. In a machine of the class described, wire feeding means, wire severing means, means controlled by the wire severing means 100 for suspending the operation of the wire feeding means, and means separate from the wire severing means for operating the suspending means.

19. In a machine of the class described, wire feeding means, means for suspending the operation of the wire feeding means, wire severing means, and manually operable means controlled by the wire severing means for rendering the suspending means inoperative substantially simultaneously with the 115 operation of the wire severing means.

20. In a machine for inserting fastenings, wire feeding means, wire severing means, a work support movable between work receiving and work clamping positions, and means 125 operable by the wire severing means to control the movement of the work support from work clamping to work receiving position.

21. In a machine for inserting fastenings, wire feeding means, wire severing means, a 130

- work support movable between work receiving and work clamping positions, and means for controlling the work support operated by the wire severing means constructed to cause movement of the work support from work clamping to work receiving position substantially simultaneously with the operation of the wire severing means to sever a fastening from the wire.
- 10 22. In a machine for inserting fastenings, wire feeding means, wire severing means, a work support, a treadle for moving the work support from work receiving position to work clamping position, means for retaining the work support in work clamping position, and means operatively connected with the wire severing means to release the retaining means.
- 15 23. In a machine for inserting fastenings, wire feeding means, a work support movable between work receiving position and work clamping position, a treadle for moving the work support to work clamping position, a latch engaging the treadle for retaining the work support in work clamping position, and means for automatically releasing said latch at a predetermined time in each cycle of operations of the machine.
- 20 24. In a machine for inserting fastenings, wire feeding means, wire severing means, a work support, a treadle for moving the work support from work receiving position to work clamping position, a latch adapted for engagement with the treadle to hold the treadle and the work support in work clamping position, and means for releasing the latch to permit movement of the treadle and the work support to work receiving position substantially simultaneously with the severance of a fastening from the wire.
- 25 25. In a machine for inserting fastenings, wire feeding means, means for suspending the operation of the wire feeding means, a treadle for controlling the suspending means, means tending whenever the treadle is in one position to urge the suspending means to inoperative position, means for rendering the suspending means operative upon movement of the treadle to another position, and means tending to move the treadle to said last mentioned position.
- 30 26. A fastening inserting machine having, in combination, wire feeding means, a finger movable between two positions in one of which it is operative and in the other inoperative to suspend the operation of the wire feeding means, means yieldingly tend-
- ing to move said finger to feed permitting position, means yieldingly tending to move said finger to feed suspending position, 60 a lever arranged for movement between two positions in one of which it renders one of said finger moving means operative and in the other of which it renders the other of said finger moving means operative, 65 and means under the control of a cyclically moving part of the machine for controlling the movement of said finger to insure the proper measurement and complete insertion of the fastenings inserted by the machine.
- 35 27. A fastening inserting machine having, in combination, wire feeding means, a finger positionable for suspending the operation of the wire feeding means, a treadle controlled rod provided with a pair of lugs one of which upon movement of the rod in one direction tends to move the finger to inoperative position thus permitting the feeding of wire and the other of which upon movement 80 of the rod in the opposite direction moves the finger to operative position to suspend the feeding of the wire, and a stop under the control of a cyclically moving part of the machine to control the movement of the 85 finger to inoperative position.
- 40 28. A fastening inserting machine having, in combination, wire feeding means, a member movable from one position to another to permit or suspend the operation of the wire feeding means, and a stop, operative under the control of a cyclically moving part of the machine to prevent movement of said member to a position to permit the feed of wire except at predetermined times, movable 90 out of the path of movement of said member under the control of said cyclically moving part.
- 45 29. A fastening inserting machine having, in combination, means for controlling the initiation of wire feed comprising a finger, means for moving the finger between feed permitting and feed suspending positions, a stop positioned to prevent feed permitting movement of the finger, and means, operative after the machine is started, to move the stop from the path of the finger to permit the movement of the latter to feed permitting position at a predetermined point in the cycle of operation of the machine.
- 50 In testimony whereof I have signed my name to this specification.

GEORGE GODDU.
